(57) **CLAIM**

The ornamental design for a climbing pole assembly, as shown and described.

DESCRIPTION

FIG. 1 is a top perspective view of the first embodiment of a climbing pole assembly;

FIG. 2 is a right-side elevation view of the climbing pole assembly shown in FIG. 1;

FIG. 3 is a left-side elevation view of the climbing pole assembly shown in FIG. 1;

FIG. 4 is a front elevation view of the climbing pole assembly shown in FIG. 1;

FIG. 5 is a rear elevation view of the climbing pole assembly shown in FIG. 1;

FIG. 6 is a top plan view of the climbing pole assembly shown in FIG. 1;

FIG. 7 is a bottom plan view of the climbing pole assembly shown in FIG. 1;

FIG. 8 is a top environmental perspective view of the climbing pole assembly shown in FIG. 1;

FIG. 9 is a top perspective view of the second embodiment of a climbing pole assembly;

FIG. 10 is a right-side elevation view of the climbing pole assembly shown in FIG. 9;

FIG. 11 is a left-side elevation view of the climbing pole assembly shown in FIG. 9;

FIG. 12 is a front elevation view of the climbing pole assembly shown in FIG. 9;

FIG. 13 is a rear elevation view of the climbing pole assembly shown in FIG. 9;

FIG. 14 is a top plan view of the climbing pole assembly shown in FIG. 9;

FIG. 15 is a bottom plan view of the climbing pole assembly shown in FIG. 9; and,

FIG. 16 is a top environmental perspective view of the climbing pole assembly shown in FIG. 9.

The dash-dash broken lines show portions of the climbing pole assembly and the environment that form no part of the

(Continued)

claimed design. The dash-dot broken lines define the bounds of the claimed design and form no part thereof. The area between the break lines forms no part of the claimed design.
